UNITED STATES PATENT OFFICE

HAROLD J. LE VESCONTE, OF WESTERN SPRINGS, ILLINOIS, ASSIGNOR TO UNION SPECIAL MACHINE COMPANY, OF CHICAGO, ILLINOIS, A CORPORATION OF ILLINOIS

BAG

Application filed October 25, 1928. Serial No. 314,908.

The invention relates to new and useful improvements in bags, and more particularly to a means useful in the closing of the bag.

An object of the invention is to provide a bag with means attached thereto for insuring the folding of the mouth portion of the bag along predetermined lines for closing.

A further object of the invention is to provide a means for forming fold lines in the mouth portion of the bag through which the holding means for closing the bag mouth may be passed.

These and other objects will in part be obvious and will in part be hereinafter more fully disclosed.

In the drawings:—

Fig. 1 is a perspective view of a bag having the improved fold line producing means applied thereto with the bag mouth folded and secured by a line of stitching.

Fig. 2 is a perspective view of a bag before it is folded and from the face thereof to which the fold producing means is attached.

Fig. 3 is a view similar to Fig. 2, but showing a slightly modified form of fold line producing means.

Fig. 4 is a view similar to Fig. 2, showing another form of fold line producing means.

Fig. 5 is a view similar to Fig. 2, but showing another form of fold line producing means.

Fig. 6 is a perspective view showing the first fold in the bag mouth portion.

Fig. 7 is a view similar to Fig. 6, but showing the second fold in the bag mouth portion.

Fig. 8 is a similar view, but showing the third and final fold in the bag mouth portion preliminary to the stitching or stapling of the same for closing.

The invention is directed to a bag which may be made of any material, but preferably of paper. It is very desirable that the bag mouth portion be folded along certain lines for the most effective closing of the bag. It

is not always easy to fold the bag mouth portion, particularly when the bag is made of paper, for directing the same to a closing means such as a stapling means or a stitching means for securing the bag mouth. In the co-pending application, Serial No. 303,924,

filed September 4, 1928, there is described a bag which is creased during the manufacture of the bag to aid in the folding of the mouth portion of the bag along predetermined lines. The present invention is directed to a means which may be attached to the bag and become a part thereof, which means may be utilized for insuring the folding of the mouth portion of the bag along predetermined lines for closing. In one form of the invention, this fold determining means is in the form of a strip which is secured to the bag mouth portion well back from the edge of the bag mouth so that when the bag mouth is folded along one edge of the strip the first or initial fold line in the bag is formed, and it is formed in a place in the bag mouth portion so as to leave ample material for the folding of the bag mouth over the end thereof, so that the securing means may be passed through the folds in the bag mouth for effectively closing the bag.

In another form of the invention, this strip is of considerably greater width and is scored along lines which will determine the lines of fold.

In still another form of the invention, a series of strips are used and the fold lines will necessarily form in between the strips.

Referring more in detail to the drawings, the invention is shown as applied to a bag which is of the usual construction. Said bag may be made of paper, fabric, or any other suitable material, but the invention is particularly adapted to a bag which is made of paper. Attached to the bag at a distance back from the mouth thereof is a strip 2 which, as shown in Fig. 2 of the drawings, is in the form of a heavy paper strip. This strip may be made of fabric or it may be in the form of a strip of glue, as indicated at 3 in Fig. 5. The extreme edge of the bag mouth is indicated at 4 in the drawings. The bag mouth is first folded along the line 5, 5 at the lower side of the strip 2. Fig. 6 shows this first fold in the bag mouth, the bag being reversed before it is folded. The portion of the bag mouth 6 extending beyond the strip 2 is next folded along the line 7—7 as indicated in Fig. 7. This fold line is determined

by the top edge of the strip 2 as viewed in Fig. 9. The remaining portion 6 of the bag mouth is then folded over the initial fold in the bag mouth as indicated in Fig. 8 and this fold line is likewise determined by the line 5-5 at the edge of the strip 2. There are three fold lines which are determined by the placing of the strip 2. The first fold line, as noted, is determined by the lower edge of the strip, as indicated in Fig. 2; the second fold line is determined by the opposite edge of the strip; and the third fold line is determined by the edge 5-5 of the strip.

The bag mouth portion, as folded along these lines predetermined by the strip 2, provides an enclosing binding extending about the mouth of the bag. The securing means, as shown in Fig. 1, consists of a line of stitching 8 which passes through the folded portions of the bag mouth and also through the strip 2. This strip 2 serves as a reinforcing means to prevent the tearing out of the holding means and to create a more efficient closure for the bag. The strip which determines the fold lines is completely housed within the folded bag mouth. As shown in Fig. 3 of the drawings, the strip for determining the fold lines is much wider. The strip is indicated at 9. Said strip is provided with score lines 10, 10 and 11, 11. In Fig. 4 of the drawings the fold determining means consists of three spaced strips 12, 13 and 14. The first fold line, in the construction shown in Fig. 3 is determined by the lower edge of the strip, the next fold line is determined by the score line 10, 10; and the last fold line is determined by the score line 11, 11.

In the structure shown in Fig. 4, the first fold line is determined by the lower edge of the strip 12, the second fold line is determined by the space between the strips 12 and 13; and the third fold line is determined by the space between the strips 13 and 14.

In both forms of structure shown in Figs. 3 and 4, the strips will be placed so that the holding means passes through all three sections of the strips in Fig. 3, and all three strips in Fig. 4. Thus it is that the bag mouth is further reinforced by these strips which serve as additional means for embedding the holding means and preventing its being torn out.

In all forms of the invention, it will be noted that there is applied to the bag so as to become a permanent part thereof, means for insuring the folding of the mouth portion of the bag along three parallel lines in succession, which lines are so disposed relative to the open end as to form from the bag material a closing binding for the bag mouth extending from one side wall of the bag to the other. This is particularly useful in connection with a machine for closing bags, as the bag mouth portion may be folded quickly and

uniformly so as to properly close the bag and may be secured by a holding means passed through said folded parts of the bag mouth. These strips for predetermining the fold lines, as noted, may be made of paper, fabric, glue, or any other suitable material, but it is desirable that it shall be a means which may be easily perforated so that a stitching mechanism may be used for closing the bag. When a single strip is used, it will insure that the first fold in the bag mouth will be made at a sufficient distance back from the extreme edge of the bag mouth so as to provide sufficient material of the bag for the folding of said bag mouth so as to enclose the bag mouth whereby when the securing means is passed through the folded portions of the bag mouth there is no chance of any material being allowed to escape from the closed mouth.

It will be understood, of course, that from certain aspects of the invention, other ways of folding the bag mouth may be found useful, and the invention is not limited to the particular way shown and described for folding the bag mouth, but rather to a folding means for insuring the folding of the bag mouth along predetermined lines.

Having fully described my invention, what I claim as new and desire to secure by Letters Patent, is:—

A paper bag adapted to be closed by stitching comprising a body portion having an open end, said body portion having means separate from the bag material secured thereto and foldable therewith, said means being arranged for insuring the folding and reverse folding of the mouth of the bag along three parallel lines in succession so disposed relative to said open end that said attaching means will form from the bag material a closing binding for the bag mouth extending from one side wall of the bag to the other, said fold forming means being disposed on one face of each fold and forming an anchorage for the stitching threads.

In testimony whereof, I affix my signature.
HAROLD J. LE VESCONTE.
